ATTORNEY

UNITED STATES PATENT OFFICE

CHARLES L. BRUSH, OF RUTH, NEVADA

SHOE CABINET

Application filed September 19, 1930. Serial No. 483,078.

My present invention has reference to a cabinet primarily designed for gentlemen's use of a size and capacity to receive therein shoes and like articles as well as implements and materials for shining shoes, together with a pivoted stand or arm having a foot rest on the top or outer end thereof which is normally held by a spring clamp in the cabinet, the materials in the cabinet being wholly concealed when the doors of the cabinet are closed and further wherein the cabinet presents a neat and artistic appearance.

To the attainment of the foregoing the invention consists in the improvement herein-15 after described and definitely claimed.

In the drawings:

Figure 1 is a face view of the cabinet with the doors opened.

Figure 2 is a transverse sectional view 20 therethrough with the doors opened and illustrating by the dotted lines the foot rest in operative position.

In carrying out my invention I produce a small artistic cabinet 1 which comprises a casing. The casing is divided into compartments by a central vertical wall 2 and by suitable shelves. The cabinet is normally closed by a pair of hinged doors 3 whose confronting edges may contact with each other and about 30 with the outer edge of the wall 2.

In one of the compartments there is arranged one or a plurality of hooks 4 from which desired articles may be suspended and all of the compartments are designed for the 35 reception of shoes and shoe polishing devices and other articles.

Pivotedly secured, as at 5, adjacent to the lower end of the casing and to the vertical wall 2 there is the angle end of an arm 6. The arm has its upper end integrally formed with a plate offset to provide a foot rest 7. One side of the foot rest travels through a notch 8 in the vertical wall 2 when the foot rest is swung into the casing and when in 45 such position the foot rest is engaged by a

spring catch, 9, for holding the same in the cabinet.

The numeral 10 designates a stop element which is secured to one side of the vertical wall 2 and against which the arm 6 contacts when the said arm is released from the catch and swung to an outward acute angle as disclosed by Figure 2 of the drawings. When in this position the owner of the cabinet may rest himself upon a chair and place his foot upon the rest plate 7 and easily and conveniently polish his shoes.

The simplicity and advantages of the construction will, it is thought, be understood and appreciated by those skilled in the art to which such invention relates so that further detailed description will not be required.

Having described the invention, I claim:

A cabinet for the purpose set forth comprising a casing, said casing having a vertical wall and an open face that is normally closed by doors, an arm having an end which is pivotally secured to one side of said wall and said arm having its upper end formed with a plate that affords a foot rest, said wall being notched at its upper end to receive one side of the foot rest when the arm is swung into the casing, a spring catch for holding the arm and foot rest in the casing and a stop element on the wall to contact with the arm for holding the same at an acute angle to the vertical when swung outwardly from the cabinet.

In testimony whereof I affix my signature.

CHARLES L. BRUSH. 80
